DUAL CHANNEL NUTATING
WAVEGUIDE FEED

Paul H. Mountcastle, Glen Burnie, Md., and William E. Snyder, Webster, N.Y., assignors, by mesne assignments, to the United States of America as represented by the Secretary of the Navy

Filed Mar. 5, 1965, Ser. No. 437,613
3 Claims. (Cl. 343—758)

ABSTRACT OF THE DISCLOSURE

A dual channel scanning device having first and second waveguides positioned in a first bushing in a stationary housing and third and fourth waveguides each having one end positioned in a second bushing mounted in a rotatable housing with the other ends of said third and fourth waveguides being mounted in an offset end of said rotatable housing, and a universal joint connecting said first and second bushings whereby rotation of said rotatable housing causes said third and fourth waveguide to be nutated.

The present invention relates to an antenna and more particularly to compact dual channel nutating waveguides for use in a parabolic microwave antenna.

Nutating devices are well-known in the radar art, and various eccentric mechanisms are provided for imparting movement to the energy receiving and transmitting end of the waveguide element in a manner to generate scanning fields representing any geometrical figure. Heretofore, single channel nutation feeds have been used that provide a main RF lobe that is displaced from the boresight axis.

Advances in the radar art now make it desirable to have dual channel nutating waveguides that provide a pair of main RF lobes displaced about the boresight axis. The present invention provides compact dual channel waveguides including a dual nutating choke joint. A rotating waveguide housing is provided that has an offset end in which a bearing is mounted to provide an eccentric mount. A dual channel waveguide is provided, and one end of the dual channel waveguide is mounted in the eccentrically mounted bearing. The other end of the dual channel waveguide is provided with a specially designed waveguide joint which is mounted in a universal joint to allow nutation.

It is therefore a general object of the present invention to provide an improved scanning device for a radar.

Another object of the present invention is to provide compact dual channel nutating waveguides for use with a parabolic microwave antenna.

Other objects and advantages of the present invention will be readily appreciated as the same becomes better understood by reference to the following detailed description when considered in connection with the accompanying drawing wherein:

FIGURE 1 is a partial sideview of a nutating waveguide assembly, partially broken away to show parts in section;

FIGURE 2 is a sectional view showing a dual channel waveguide joint;

FIGURE 3 is a perspective view, partially broken away, showing a universal joint; and

FIGURE 4 is an exploded view of the universal joint shown in FIGURE 3.

Referring now to FIGURE 1 of the drawing, there is shown a stationary housing 10 to which there is rotatably mounted a rotatable waveguide housing 11 which is provided with an offset end 12. A bearing 13 is mounted in offset end 12 and a bushing 14 is mounted in the inner

2

race of bearing 13. A pair of rectangular waveguides 15 and 16 are positioned in bushing 14. One end of waveguide 15 is positioned in close proximity to waveguide 17, and one end of waveguide 16 is positioned in close proximity to waveguide 18. Waveguides 17 and 18, which are rectangular and similar in cross-section to waveguides 15 and 16 are stationarily mounted in stationary housing 10.

As best shown in FIGURES 2, 3, and 4 of the drawing, one end of each of waveguides 15 and 16 are connected to stationary housing 10 through a universal joint 21. Bearing member 22 of universal joint 21 is pivotally connected to bushing 23, which supports the stationary waveguides 17 and 18. Bushing 24, which supports one end of waveguides 15 and 16, is also pivotally connected to bearing member 22. By way of example, bearings 25-28 are provided in bearing member 22 and short shafts 31 and 32, which are attached to bushing 23, are fitted in the bores of the inner races of bearings 25 and 26, respectively. Likewise, short shafts 33 and 34, which are attached to bushing 24, are fitted in the bores of the inner races of bearings 27 and 28.

Referring particularly to FIGURE 2 of the drawing, there is shown the RF joint configuration for the broad wall of the rectangular waveguides. It is not necessary to choke the narrow wall. The distance between the stationary waveguides and the nutating waveguides is shown to be equal to the distance a . It has been determined by experimentation that the optimum value for a is given by the following formula:

$$a = \frac{C}{0.3} \tan \alpha$$

where C is the distance between the pivot point and the outside edge of the waveguides and α is the offset angle.

Bushing 23, which holds stationary waveguides 17 and 18, is provided with two end flanges 35 and 36 and a center flange 37. Likewise, bushing 24, which holds nutating waveguides 15 and 16 is provided with two end flanges 38 and 39 and a center flange 41. The length of the flanges is shown as b , which is equal to a quarter wave length and, therefore, would change depending upon what frequency band coverage is desired. Center flanges 37 and 41 serve as a center choke and greatly limit any undesired cross coupling. By adding absorbing material 42 to the center flange 37, cross coupling can be reduced even further.

In operation, when waveguide housing 11 is rotated, waveguides 15 and 16 are nutated to transcribe a cone in space with the universal joint pivot point as the vertex and the offset angle as one half the included cone angle. The nutating waveguides are prevented from rotating by universal joint 21.

It can thus be seen that the present invention provides improved dual channel nutating waveguides for use with a parabolic microwave antenna. Obviously many modifications and variations of the present invention are possible in the light of the above teachings. It is therefore to be understood that within the scope of the appended claims, the invention may be practiced otherwise than as specifically described.

What is claimed is:

1. A dual channel scanning device comprising: a stationary housing, first and second waveguides attached to said housing, a waveguide housing rotatably mounted to said stationary housing about an axis of rotation and having an offset end the axis of which intersects said axis of rotation, a bearing mounted in said offset end of said waveguide housing, and third and fourth waveguides each having one end mounted in said bearing and the other ends attached

to said stationary housing through a universal joint, one end of said third waveguide being adjacent one end of said first waveguide and one end of said fourth waveguide being adjacent one end of said second waveguide, and whereupon rotation of said waveguide housing causes nutation of said third and fourth waveguides.

2. A dual channel scanning device comprising:
 a stationary housing,
 a first bushing attached to said housing and having first and second end flanges and a center flange,
 first and second waveguides supported by said first bushing, said first waveguide having an end terminating in an opening between said first end flange and said center flange and said second waveguide having an end terminating in an opening between said second end flange and said center flange,
 a waveguide housing rotatably mounted to said stationary housing about an axis of rotation and having an offset end the axis of which intersects said axis of rotation,
 third and fourth waveguides each having one end rotatably mounted in said offset end,

5

15

a second bushing supporting said third and fourth waveguides and having first and second end flanges and a center flange, said third waveguide having an end terminating in an opening between said first end and center flanges of said second bushing and said fourth waveguide having an end terminating in an opening between said second end and center flanges of said second bushing, and

a universal joint connecting said first and second bushings whereby rotation of said waveguide housing causes nutation of said third and fourth waveguides.

3. A dual channel scanning device as set forth in claim 2 wherein a strip of absorbing material is added to the center flange of said first bushing thereby reducing cross-coupling of energy between waveguides.
